INVENTOR

Chester H. Pond,

UNITED STATES PATENT OFFICE.

CHESTER H. POND, OF NEW YORK, N. Y., ASSIGNOR TO THE TIME TELEGRAPH COMPANY, OF SAME PLACE.

DESIGN FOR AN ELECTRICAL CONDUCTOR.

SPECIFICATION forming part of Design No. 14,451, dated November 27, 1883.

Application filed September 24, 1883. Term of patent 14 years.

To all whom it may concern:

Be it known that I, CHESTER H. POND, a citizen of the United States, residing in New York, in the county and State of New York, 5 have invented and produced a new and original Design for Electrical Conductors, of which the following is a specification.

My design is more especially applicable to telegraphic conductors which are covered with 10 fibrous insulating material, although it may be applied to any other material which may form the surface of the conductor.

The design consists in dividing the surface 15 of the conductor into sectional bands or zones of different shades of color. The sections may be of any desired length, which may be uniform throughout the series.

In the accompanying drawing I have illustrated my design as applied to an ordinary 20 telegraph-wire, the sections *a a a a* being di-

vided into uniform lengths of about one inch. In practice any suitable kind of shading material may be employed, and it may be applied in any convenient and well-known manner.

The design may be applied to telegraphic and telephonic conductors as well as to conductors for conveying an electric current.

I claim—

The design for an electrical conductor herein 30 shown and described, consisting of a series of zones, each zone being of a different shade from that of its adjacent zones, as described.

In testimony whereof I have hereunto subscribed my name this 22d day of September, 35 A. D. 1883.

CHESTER H. POND.
